RAILWAY TIE PLATE

George T. Willard, Chicago, Ill.

Application May 22, 1931, Serial No. 539,203

3 Claims. (Cl. 238—304)

This invention relates to railway tie plates.

In a co-pending application, filed May 22, 1931, Serial No. 539,201, I have shown various forms of plates, provided with an upwardly projecting shoulder at each side of the rail base, and various forms of rail retaining devices mounted on said shoulders to provide a yielding or non-fixed connection between rail and plate for the purpose of permitting wave motion of the rail under load without injury to track such as results from loosening of spikes which attach the plate to the tie or which results from the lifting of the plate and tie from the ballast when the connection between rail plate and tie is a rigid, non-yielding one.

In another co-pending application, filed May 22, 1931, Serial No. 539,202, I have shown means for converting the normal yielding connection between rail and tie plate into a rigid non-yielding connection which is desirable for the purpose of raising the track by jacking up the rail between ties without distorting or otherwise injuring the yielding connecting means.

As explained in said co-pending applications, the shoulders located at each side of the rail bearing surface of the plate with which the several rail retaining devices cooperate for their intended purposes, may be produced by rolling the same integrally with the plate or by rolling and bending, or by casting from steel or iron. When such shoulders are provided with openings or recesses the axes of which are at an angle to and not parallel with the axes of the spike holes which are commonly punched vertically through the horizontally disposed plate, it is necessary, after the rolling and spike hole punching operation, to subject the plate to special machine operations for cutting the slots or openings in the shoulders. This extra handling and cutting of slots in plates in which said shoulders are integrally formed with the plates adds substantially to the expense of manufacture. It is one of the objects of the present invention to devise a method of construction of shouldered plates by which the cost of production will be materially lessened.

The main object of the present invention is to economically produce tie plates provided with various forms of shoulders with which rail retaining devices cooperate, which shoulders may be cast or otherwise formed separately from the plate and welded to the plate to firmly secure the parts together.

Plates embodying the present invention may be made of rolled steel, cast steel or cast iron

and may be secured to the tie with cut spikes, screw spikes or bolts, or both cut spikes and screw spikes or bolts.

In the drawing, I have chosen to embody the various forms of my invention in tie plates provided with flat tie bearing surfaces but obviously the plate bottom may be provided with transversely disposed ribs or with reinforced portions located at the stress points under the rail flange edges, or both, and the reinforced portion may be provided with a short rib depending from and extending longitudinally of the reinforced portion and parallel with the rail edges. Any desired bottom construction may be used but I prefer to embody my invention in plates wherein all ribs and reinforcing members on the plate bottom are formed with rounded non-fiber cutting edges.

In the drawing:

Fig. 1 is a perspective view of a tie plate embodying my invention, showing a section of rail in place on the plate.

Fig. 2 is a vertical sectional view through the left side of the plate shown on Fig. 1.

Fig. 3 is a vertical sectional view of a modified form of plate embodying my invention.

Fig. 4 is a section taken on the line 4—4 of Fig. 3 looking in the direction indicated by the arrows.

In each of these figures the rail is indicated at 10, the rail flanges at 11, the tie plate 12 and the tie 13. A shim of compressed treated wood or fiber 14 is shown between the rail and the rail bearing surface of the plate.

In that form of my invention shown in Figs. 1 and 2, the plate 12 has welded to its grooved top at opposite sides of the rail bearing surface, an upright shoulder 15 provided with a base 16 and a hook shaped flange 17. The base 16 may be provided with a downturned and inturned end 16', extending into the slot 12'. The plate 12 is preferably rolled with a groove extending transversely of the plate bottom and outwardly of each side of the rail edges, which groove communicates with the slot 12', to accommodate the part 16'. Near one side the shoulder 15 is apertured as indicated at 18. A rail retaining device is mounted on the shoulder 15—17. It is made of spring metal, consisting of a rail bearing arm 19, a plate bearing arm 20, and an intermediate curved member 21 joined to the plate bearing member 20 by a sharply curved portion 22 which bears against the hook 17 of the shoulder 15. This rail retaining device provides a yielding connection between rail and plate. A wedge or spike (not

shown) may be inserted through the aperture 18, so that its end will bear on the rail flange 11 and its head on the plate 12, when it is desired to produce a rigid connection between rail and plate for the purpose of raising the track by jacking up or lifting the rail between ties. Without such provision the strain on the spring metal rail retaining device, when the rail is lifted, is unduly great and apt to result in distorting or breaking the spring. Screw bolts 23, for attaching the plate to the tie, and spike holes 24 are shown.

In the modification shown in Figs. 3 and 4, the shoulder 15 is secured to the plate by welding the base 16 to the grooved top of the plate 12, adjacent 15 a rail abutting shoulder 25 on the plate. The shoulder 15 is apertured at 26 for the reception of a spring metal rail retaining member 27. This member 27 is provided with a rail bearing arm 28 and a plate bearing arm 29, the reduced end 30 20 of the arm 28 being held in a recess 31 cut into the plate 12. Instead of a recess 31 the plate may be provided with a groove in which the end 30 may be retained. The slot or aperture 26 may be made wider than the spring 29 to leave room 25 for the insertion of a wedge for bearing on the plate and rail to produce a rigid connection when that is desired for track raising purposes, as heretofore explained. Welding of the shoulder 15 to the plate 12 is indicated at 32.

30 By using conventional rolls for forming the plate body and welding to the plate the preformed,

specially shaped or slotted shoulders required for cooperating with rail retaining devices such as herein described, I have substantially reduced the cost of production as compared with the cost of an integrally formed plate.

Changes may be made in details of construction without departing from the scope of my invention and I do not intend to be limited to the exact form shown and described except as set forth in the appended claims.

I claim:—

1. A tie plate having a rail bearing surface provided with a transversely extending groove in the top of the plate adjacent each edge of said rail bearing surface, and a rail abutting shoulder 15 welded to the grooved surface.

2. A tie plate having a rail bearing surface provided with a transversely extending groove in the top of the plate adjacent each edge of said rail bearing surface, and a preformed base and rail abutting shoulder, said base being welded to 20 the grooved surface of the plate.

3. A tie plate having a rail bearing surface provided with a transversely extending groove in the bottom of the plate, located outwardly of each 25 edge of the rail flange, the plate being slotted from its top to said groove, a shoulder adapted to project upwardly from the plate and extending downwardly into said slot and groove and welded to slot and groove walls.

GEORGE T. WILLARD. 30
